UNITED STATES PATENT OFFICE.

CHARLES F. WALTHER, OF BUFFALO, NEW YORK, ASSIGNOR TO SHERMAN S. JEWETT & CO., OF SAME PLACE.

DESIGN FOR A HEATING-STOVE.

SPECIFICATION forming part of Design No. 21,440, dated March 29, 1892.

Application filed October 24, 1891. Serial No. 409,722. Term of patent 7 years.

To all whom it may concern:

Be it known that I, CHARLES F. WALTHER, a citizen of the United States, residing at Buffalo, in the county of Erie and State of New 5 York, have invented and produced a new and original Design for Heating-Stoves, of which the following is a specification.

My design has for its object to render ornamental and more attractive a heating-stove; 10 and it is illustrated in the accompanying drawing, which is a perspective view of a stove ornamented with my design.

The characteristic features of this design are the novel configurations and surface 15 ornamentations of the segregable parts of the stove and of the stove as a whole, as will be hereinafter pointed out.

In order that the conventional box-like appearance of the ordinary heating-stoves, particularly those which burn wood, may be departed from, I make the ends of the stove, as seen from the front, to curve inward near their upper ends, as at 6 6, and I make the 20 top of curved or arch shape, from the central 25 portion of which top there rises a base or pedestal s, having sloping ends and a flat top, which base or pedestal is adapted to receive a supplementary ornamental top piece, to be hereinafter described. The skirting of the 30 stand, which is carried by the legs and on which the stove-body rests, is ornamented along its front portion with three scallop-like 35 designs, the central one a being the largest and arranged with its convex edge downward, while the other two smaller scallop designs b are arranged at the ends of the ornament a with their convex edges upward. The base 40 of the stove proper immediately above this portion of the skirting is ornamented with 45 tracery c, the lines of which cross each other to form lozenge-shaped figures. The end pieces of the skirting of the stand are ornamented with single scallop-shaped designs d, and the base of the stove proper immediately above 50 with tracery e. The legs F are joined to the skirting and are so ornamented that their designs blend with those of the skirting. The design of each leg consists of a leaf or branch f, having the stem portion rising from the toe 55 of the leg and the foliated portion flared and ornamenting the upper expanding front face

of the leg, and scroll or volute ornaments g at either side of the ornament f, where the leg joins the skirting. The toe of the leg has a conventionalized leaf ornament h. The brackets i for the foot-rests are in general outline of ogee form, the convex curve of each bracket resting upon the skirting directly above the leg, so that it appears as though this bracket 60 sprang from the skirting of the stove-stand. To heighten this effect, the surface ornamentation of the bracket is in harmony with the 65 design of the skirting. Thus the whole bracket is ornamented with a conventionalized leaf or branch design, the lower portion i of which, resting upon the skirting, represents the stem, the upper part j being foliated. The cross-bar K, which forms the foot-rest proper, extends between the foliated portions of the 70 bracket and is itself ornamented, its central portion having a scallop design k.

The parts thus far described are shaped and ornamented, as has been described, so that the effect is that of one harmonious design, there being no perceptible break or separation between the different parts, which together constitute what may be termed the "stand" or "support" of the stove, upon which the stove proper is seated.

The lower front door L of the stove, containing the draft-damper, is ornamented along its outer edge by a border l, while the draft-openings are surrounded by circular ornaments m.

The upper front door N is ornamented by 85 a design, the characteristic features of which are the scallop-shaped ornaments n n at the top and bottom, respectively, of the door, the central circular design o, and the tracery p, there being quarterfoils q at the crossings of 90 the lines of the tracery.

The holder or frame R for the ornamental tile r is secured to the front of the stove above the large door N and serves to ornament the upper front portion of the stove. It has a 95 substantially centrally-arranged opening for the tile r, surrounded by an ornamental beaded rim 1, and above which is arranged a spreading fan-shaped ornament 2. Below the rim there is situated a smaller shell-shaped 100 ornament 3, and either side thereof are arranged the arabesque foliated designs 4 4, ex-

tending around the rim between the ornaments 2 and 3.

5 5 are foliated portions of the tile-holder extending laterally from the shell ornament 3 and below the foliated portions 4 thereof, beyond which their expanding ends extend.

The sloping sides of the pedestal or base *s*, which rises from the curved or arched top plate, are ornamented by the tracery *u*. *v* 10 designates an ornament, which is secured to the curved top near where it joins the end of the stove, one being on either side of and below the pedestal. The corners of the stove-top are covered by cap-pieces *w*, having a 15 shell-like shape and ornamentations. The ornamental parts *v* and *w* just referred to are separable from the top. Upon the base or pedestal *s* is placed the supplementary ornamental top *T*. It is of dome shape and has 20 seated upon it the figure of a nude child holding a lighted torch. The sides of this dome-shaped top are ornamented with tracery *x* and its corners with separable shell-shaped cap-pieces *y*.

25 The end door *Z* of the stove has an ornamental border *z* surrounding it, and oblong ornamental designs *z'* surrounding the draft-holes in the upper part of the door.

What I claim is—

30 1. In a design for a stove, the stove-body having the ends curved inward near their upper ends and having the curved or arch-shaped top from which rises a pedestal or base, substantially as shown and described.

35 2. In a design for a stove, the novel configuration of the base or support, consisting of the skirting, the legs, and the foot-rest, the brackets of which latter rise from the skirt,

whereby a single harmonious design is produced, substantially as shown and described. 40

3. In a design for a stove, the design for the skirting of the stand upon which the stove-body rests, having the portions between the legs ornamented with the scallop-shaped surface ornamentations, substantially as shown 45 and described.

4. In a design for a stove, the leg having thereon the ornament *F*, consisting of a stem rising from the toe of the leg and terminated in an expanded foliated top covering the upper front face of the leg, substantially as shown and described.

5. In a design for a stove, the design for the foot-rest and its supporting-brackets, substantially as herein shown and described. 55

6. In a design for a stove, the design for the lower front or damper door, substantially as shown and described.

7. In a design for a stove, the design for the upper front door *N*, substantially as shown 60 and described.

8. In a design for a stove, the tile holder or frame of the novel configuration and ornamentation substantially as shown and described. 65

9. In a design for a stove, the ornamental top *T* of dome shape, surmounted by a figure, substantially as shown and described.

10. The design for a heating-stove, substantially as shown and described. 70

In testimony whereof I affix my signature in presence of two witnesses.

CHARLES F. WALTHER.
